UNITED STATES PATENT OFFICE.

EDGAR B. BICKER, OF ST. LOUIS, MISSOURI, ASSIGNOR OF ONE-HALF TO ERNEST EIKHOFF, OF ST. LOUIS, MISSOURI.

CIGAR-CAN.

1,164,913.

Specification of Letters Patent. Patented Dec. 21, 1915.

Application filed November 9, 1914. Serial No. 871,198.

To all whom it may concern:

Be it known that I, EDGAR B. BICKER, a citizen of the United States, and resident of St. Louis, Missouri, have invented certain new and useful Improvements in Cigar-Cans, of which the following is a specification containing a full, clear, and exact description, reference being had to the accompanying drawings, forming a part hereof.

10 My invention relates to improvements in cigar cans, wherein the lid is hingedly secured to the can and a movable strip serves to lock the lid in a closed position and also serves as a lever for opening the lid, and the 15 objects of my invention are to provide a cigar can with a hinged lid and to arrange a simple means whereby to lock the lid in a closed position, as well as to facilitate moving the lid to dispense the cigars.

20 With the above objects in view, my invention consists in certain novel details of construction and arrangement of parts herein-after fully described, pointed out in my claims and illustrated in the accompanying 25 drawings, in which:

Figure 1 is a sectional elevation of a cigar can embodying my improvements; Fig. 2 is an inverted, sectional plan, taken on the line 2—2 of Fig. 1; Fig. 3 is a sectional elevation 30 of the can, showing the lid in an open position; Fig. 4 is a fragmental cross-sectional elevation taken on the line 4—4 of Fig. 2; and Fig. 5 is an enlarged sectional elevation 35 illustrating the hinge.

Referring by numerals to the accompanying drawings: 6 designates the can, which is preferably constructed of sheet metal in the conventional cylindrical form and provided with a bottom 7 secured in place by 40 crimping, and with an inturned bead 8 at its upper margin and adjacent the inturned bead 8 I form through the body of the can a slot 9.

The numeral 10 designates the lid, which 45 is preferably sheet metal of disk form and provided with a down-turned peripheral flange 11, which when the lid is closed loosely surrounds the can body so that it may be readily lifted thereover.

50 A portion 12 of the flange just referred to

is of greater length than the balance of the flange so that it may be extended through the slot 9 in the can body and bent to act as a hinge connection between the lid and can. Formed through the flange of the lid 55 immediately over the hinge portion 12 thereof is a slot 13, and struck from the lid are the spaced pairs of ears 14.

Supported upon the ears and arranged to slide therebetween and through the slot 60 13 is a strip 14^a of relatively inflexible material, preferably sheet metal, having its one end provided with an upturned bead 15 and its opposite end with a hook 16, the upturned bead providing means for moving the strip 65 and the hook providing means, in conjunction with the bead 8 of the can, for securing the lid in a closed position.

In order to limit the movement of the strip to prevent its complete withdrawal 70 from the lid, I provide the lateral lugs 17 adjacent the hook ends of the strip which will engage the ears struck from the lid.

When the can is filled the lid is closed and the strip moved so that its hooked end 16 75 will engage beneath the bead 8 of the can, thereby locking the lid closed and tending to obviate the breaking of labels, revenue stamps and the like, adhesively secured over the lid and can sides.

To open the can the upturned bead 15 of the strip is engaged and through it the strip moved, disengaging the hooked end 16 from the bead 8 of the can, its withdrawal being limited by the lateral lugs 17 and its withdrawn end utilized as a lever for tilting the lid on its hinge to an open position.

Having thus described my invention, what I claim as new therein and desire to secure by Letters Patent of the United States is:— 90

1. In combination with a can having a flanged lid, hingedly connected with the can, the flange having a slot therein, guides struck from the lid in line with said slot, and a member arranged to slide through said 95 guides and slot to extend beyond the body of the can, substantially as shown and for the purposes stated.

2. In combination with a can having near its top an internal projection, a lid, and a 100

slotted hinge connecting the lid with the can, a member slidably carried by the lid for movement in the slot of said hinge and arranged to engage the internal projection of
5 the can, for the purposes stated.

In testimony whereof, I have signed my

name to this specification, in presence of two
subscribing witnesses.

EDGAR B. BICKER.

Witnesses:
